UNITED STATES PATENT OFFICE.

JACKSON R. LUSK, OF WILLIAMSBRIDGE, NEW YORK.

RECEPTACLE.

1,119,619.

Specification of Letters Patent.

Patented Dec. 1, 1914.

Application filed January 8, 1914. Serial No. 311,014.

To all whom it may concern:

Be it known that I, JACKSON R. LUSK, a citizen of the United States of America, and resident of Bronxwood Park, Williamsbridge, in the county of Westchester and State of New York, (whose post-office address is Bronxwood Park, Williamsbridge, New York,) have invented certain new and useful Improvements in Receptacles, of which the following is a specification.

This invention relates broadly to receptacles and more particularly to that type of receptacle which includes a main body or container, a demountable cover, and a handle or bail associated therewith.

One of the objects of this invention is to provide a receptacle of the above class whereby the handle or bail and an auxiliary means carried by the receptacle or the cover may be interengaged to set up a reaction between the bail and the cover, which will tend to keep the cover in place at all times.

Another object is to provide an embodiment of this invention in which such auxiliary means shall be carried by the cover and shall be utilizable when desired for removing the cover from the container.

Other objects and aims of this invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claim.

Referring now to the accompanying drawing, which is to be taken as a part of this specification, and which discloses one of the various possible embodiments of the invention as at present preferred: Figure 1 is a view in elevation, partly broken away, showing an embodiment wherein an auxiliary means is carried by the cover and interengaged with a bail carried by the container; Fig. 2 is a view of the parts shown in Fig. 1, looking in the direction of the arrow shown in Fig. 1; Fig. 3 is a detail perspective view, showing more clearly the engagement of bail 8 and auxiliary bail 11 as disclosed in Figs. 1 and 2; and Fig. 4 is a view similar to Fig. 3, but showing a possible variation in the construction of the auxiliary bail 11.

Similar reference characters refer to simi-

lar parts throughout the several views of the drawing.

Referring now particularly to Figs. 1, 2 and 3, reference numeral 6 indicates an open-topped type of container, as a garbage vessel. This container carries on the outer surface of its cylindrical wall a pair of oppositely disposed and transversely apertured ears 7. These ears support in the usual manner a bail 8 of wire or the like. A demountable cover 9 is shown as mounted upon the container. Cover 9 carries the straps 10, within each of which is pivotally mounted as disclosed a terminus of an auxiliary bail 11. This auxiliary bail 11 may be bent substantially as shown in Figs. 2 and 3. Bail 8 is in the figures last-mentioned provided with a notch 12; this may be formed either by bending the bail wire, as shown, or by cutting out the notch to the required depth; and the auxiliary bail 11 is similarly provided with a notch 13.

Having thus described this embodiment of this invention, the operation thereof, which should largely be obvious, may now be described. Normally bail 8 by gravity depends from its supporting ears 7, alongside the outer surface of the cylindrical wall of the container 6, as indicated in dotted lines in Figs. 1 and 2; and normally the auxiliary bail 11 by gravity lies flat upon the upper surface of cover 9. When it is desired to lock the cover in place upon the container, after said cover has been mounted on the latter, auxiliary bail 11 is manually raised to its Fig. 1 position, and bail 8 is similarly raised to its full line location, so that the notch carried by bail 8 may be sprung into interengagement with the notch carried by auxiliary bail 11, as shown in Fig. 1. The cover is thereby clamped into place upon the container; and the bail 8 is substantially vertically arranged so it may be manually caught hold of, to lift the container.

It will be noticed that the auxiliary member 11 is provided with an offset part 15 which by its engagement with the cover 9 (see Fig. 1), limits the pivotal movement of bail 11 in one direction (to the right in Fig. 1); and this offset part 15 has such an angular relation to the plane of the bail 11, and the relative arrangement of the notches 12 and 13 is such that when these notches are interengaged the bail 11 inclines somewhat away from the vertical. Accordingly, re-

ferring to Fig. 1, a blow against auxiliary member 11 to the right, could not release the two bails from their interengagement, while a blow against bail 11 to the left would have 6 so overcome the inclination of bail 11 away from the vertical, and therefore the danger of release by such a blow to the left is at least minimized.

It will be seen that the vertical locking 10 position of auxiliary bail 11 will not interfere with manually taking hold of bail 8, because as best indicated in Fig. 1, the fingers of the hand may quickly and conveniently grasp bail 8 in such a manner that 15 auxiliary bail 11 will without discomfort separate one finger from another. It is also obvious that with bail 8 disposed as shown in dotted lines, cover 9 may be with great convenience demounted from the container, 20 since any upward pull upon said bail 11, in the absence of engagement of the latter with bail 8, will remove the cover from the container; while if said bails be interengaged as shown, a pull upon either of them will insure 25 that the entire covered container 6 will be lifted.

Referring now particularly to Fig. 4, it should be understood that the bails 8 and 11 disclosed therein are preferably suitably carried 30 one by the container and the other by its cover. It will be noted that the showing of Fig. 4 differs from that of Fig. 3 in that auxiliary bail 11 is looped upon itself, as shown to form the eye 14, for bail 8 is here 35 preferably formed similar to the bail 8 shown in Figs. 1, 2 and 3. Were bail 8 carried by the container 6 and bail 11 carried by the cover 9, a manner in which the parts may be assembled is as follows, that is, first, 40 bail 8 is inserted through the eye 14 preferably before one of the terminal eyes carried by said bail 8 is formed thereon or bail 8 is first completely formed and the eye 14 of bail 11 is next formed so as to encircle 45 bail 8, and second, bail 8 is mounted upon receptacle 6, and bail 11 upon the cover 9, as above described. The functions of the bails 8 and 11 shown in Fig. 4 are or may be 50 similar to those described in connection with the bails 8 and 11 shown in Figs. 1, 2 and 3. But an additional advantage is present in connection with the construction shown in Fig. 4, it is thought, for the reason that

when bail 11 may be sufficiently turned upon its pivots so that eye 14 sufficiently travels 55 longitudinally of bail 8 to permit of the demounting of cover 9 from the receptacle 6, thereupon or simultaneously therewith bail 8 may be swung on its pivots to permit of its assuming approximately the dotted line 60 location shown in Figs. 1 and 2. It will follow that despite the demounting of cover 9 thus accomplished, bails 8 and 11 will remain in interengagement sufficiently to prevent the separation from container 8 of its 65 cover 9 and a possible misplacement of the latter.

Inasmuch as many changes could be made in the above construction, and many apparently widely different embodiments of my 70 invention could be made without departing from the scope thereof, it is intended that all matter contained in the above description or shown in the accompanying drawing shall be interpreted as illustrative and not in a 75 limiting sense.

It is also to be understood that the language used in the following claim is intended to cover all the generic and specific features of the invention herein described and 80 all statements of the scope of the invention which, as a matter of language, might be said to fall therebetween.

I claim:—

The combination with a vessel and its 85 bail, of a cover for the vessel provided with a bail-holder, adapted to swing in a plane at right angles to the movement of the bail, said bail-holder and bail having inter-engaging notches, and the bail-holder being provided with a stop for limiting its pivotal movement in one direction, the bail-holder being inclined with respect to the cover when it has reached the limit of movement defined by said stop, and the notch of the bail- 90 holder being in engagement with the notch of the bail when the bail-holder is in such inclined position.

In witness whereof, I have hereunto signed my name in the presence of two wit 100 nesses.

JACKSON R. LUSK.

In the presence of—

ALDA L. MILLER,
MARY H. LEWIS.
